UNITED STATES PATENT OFFICE.

KARL KIEFER, OF CINCINNATI, OHIO.

FILLING MACHINE.

Application filed December 18, 1922. Serial No. 607,756.

My invention relates to machines for filling containers with liquids, and more especially to such machines which are designed to place in each container a uniform weight of liquid.

The object of my invention is to simplify and increase the reliability and accuracy of such machines, and especially to provide a compact construction and arrangement which will occupy small floor space relatively to its capacity, easy to adjust for containers of various sizes. Other objects will appear in the course of the ensuing description.

I attain these objects by the device illustrated, for example, in the accompanying drawings, in which—

Figure 1 is a side elevation of the complete machine;

Fig. 2 is a partial horizontal cross-section on the plane of the line 2—2 of Fig. 1, showing the yoke, parts of which are broken away, for clearness, and the scale beam resting thereon, the view being enlarged;

Fig. 3 is a partial front elevation of the upper part of the machine, on the same enlarged scale as Fig. 2;

Fig. 4 is a vertical front-to-rear section on the plane of the line 4—4 of Fig. 3;

Fig. 5 is a partial plan view of the machine, with the reservoir lid removed, and middle parts of the float being broken away, to show the toggle float-and-valve connection;

Fig. 6 is a detail perspective view of the valve-holder and part of its stem, further enlarged; and

Fig. 7 is a similar view of a valve to fit the holder, similarly enlarged.

The tripod base 1 centrally supports the standard 2, which is threaded from the base up to near its top. The yoke 3 comprises a hub 4 embracing the standard 2, split to form jaws 5 which are drawn together by a screw 6 to clamp the yoke 3 rigidly on the standard. A handwheel 7 has its hub in the form of a nut 8 traveling on the threads of the standard 2, for running the yoke 3 up or down when its clamping jaws 5 are loosened.

This yoke 3 extends laterally from its hub, equally on both sides, curving upward and terminating in crotches 9 in the transverse vertical plane of the standard axis; and it has front and rear arms 10 with eyes 11 at their ends forming rests for the scale pans

or tables 12, which have stems 13 (Fig. 1) down through the eyes 11, with pivots 13' passing transversely through them and through the outer ends of links 14, the inner ends of which are extended into sockets in the front and rear, respectively, of the hub 4, with pivots 14' passing transversely through the links 14 into the sides of the hub sockets. The scale beam 15 comprises separate members 16 straddling the standard 2, with knife edges 17 in the crotches 9, and having transverse integral parts end parts 18 joining the ends of the members 16 together, with knife edges 19 at opposite ends receiving crotches 20 of the tables 12. These tables are kept almost exactly vertical by the links 14, which are used instead of a single link connected to both stems 13 as usual in balances, in keeping with my improved symmetrical arrangement of the column 2 and the scale, with the tables 12 symmetrical to the front-to-rear vertical plane of the standard axis.

The reservoir 21 comprises a cylindrical shell and a base 22 sloping to an outlet 23 at the center, below which outlet is a hub 24 fitting on the top of the standard 2 rigidly. At its rear, near its bottom, the reservoir has the inlet 25, which may be connected to a source of supply of liquid by a hose or the like. This inlet has a valve seat around it, and a valve 26 slides in the inlet, guided by its radial vanes 27 against the inlet walls. The toggle 28 comprises a link 29 with one end pivoted to the valve 26, and a two-part link 30 with one end pivotally connected to the front wall of the reservoir by a pin 31 in slots 32 formed in lugs on the reservoir base, in which it is held by pins 33. Both links 29 and 30 are pivoted to the stem 34 of the float 35, which is a cylindrical liquid-tight hollow body with its stem at its center, projecting downwardly. This stem 34 extends through the hollow core 35' of the float and has a nut 34' above and lock-nuts 34'' below, for adjusting the float up and down on the stem, thus adjusting the height of liquid maintained in the reservoir. A lid 36 closes the top of the reservoir.

The spout 37 comprises the horizontal part leading radially forward from the reservoir outlet 23, and an upright part 38. A bracket 39 has a front part embracing this part 38 below the horizontal part and has its rear end clamped around the standard 2.

The lower end of this spout part 38 is threaded exteriorly, and the nozzle 40, screwed thereon, has the internal upwardly facing valve seat 40' around its central outlet. The casing 41 leads up from the top of the spout part 38 along the front of the reservoir 21 above the maximum height of liquid in the reservoir, having on its top a guide cap 42 with a central opening.

10 The valve holder 43 comprises radial vanes 44 and the bottom 45 spaced from the spout walls, which the vanes 44 guidingly bear on, leaving an annular liquid passage. This bottom 45 has a radial T-slot 46 (Fig.

15 6) open at one side only; and the valve 47 (Fig. 7) of the diameter of the bottom 45, has a T-shaped projection 48 slid radially into and accurately fitting the T-slot. The bottom of this valve 47 fits the valve seat 20 40'; these being, as herein shown, conical.

The valve stem 49 has its lower end fixed centrally in the top of the valve holder 43 and extends up through the casing 41 and out through the guide opening in the cap 42, above which it carries a suitable connecting head 50.

The rocking member 51 comprises the shaft 52 journaled transversely in a bearing formed in the front of the upright spout part 38 opposite the horizontal part, and elements 53 and 54 at opposite sides of the spout, fixed on the shaft; the one at the left (Fig. 3) extending backward and being connected to the head 50 of the valve stem by a link 55 extending up close alongside the casing 41. The element 54 at the right extends down in the form of a pawl engaged by a detent 56 on the end of a lever 57 having its fulcrum in a lateral lug 58 on the bracket 40 39 and extending backward beyond the standard 2, with a counterpoise 59 near its rear end, adjustable therewith and clamped thereto by a screw 60 (Fig. 1). The front arm of this lever is very short, and the 45 weight of the much longer rear arm and counterpoise 59 holds its detent 56 up in engagement with the pawl of the element 54. Preferably, the pawl and detent are of hardened steel, to retain their accuracy of engagement. Also, preferably, an adjusting screw 61 is threaded up through the bracket 39 just to the rear of the lever fulcrum, as a stop for the rear arm of the lever. This permits the rise of the lever detent, on the front arm, to be so limited that only a very slight engagement of the pawl and detent is made, so that the pawl is released by a very slight swing of the lever 57.

The element 54 also extends up from the shaft 52, in the form of a handle 62, to which is pivoted the rod 63 of a plunger 63' in a dash-pot 64 having its rear end pivoted on a stud 64' on the side of the bracket 39; this plunger, when the spout valve descends, forcing air out through the rear

outlet of the dash-pot, more or less restricted by a regulating screw 65 (Fig. 1).

The push-rod 66 is clamped in a clamp-head 67 which is clamped to an edge of the rear scale pan or table 12 at the right, and 70 extends upward and over to the left, in a terminal horizontal part 68 (Fig. 3) under the long rear arm of the lever 57.

As liquid enters the reservoir 21 through its inlet 25, it raises the float 35, which pulls up the links 29 and 30, tending to straighten the toggle formed by them and increasing its effective length, until it forces the valve tightly shut.

With the float adjustable up and down on its stem 34 as before described, and the ample opening of the inlet valve permitted by the toggle operation as controlled by this float, and the prompt and effective closure thereby upon the required liquid level 85 being reached, the device may be made to maintain a practically constant level of liquid in the reservoir 21; so that the "head" 90 of liquid, causing flow out through the spout 37 is practically constant. The toggle action is very strong and certain.

The parts are so designed that when the pawl part of the element 54 is held by the lever 57 as before described, the opposite element 53, through the connection of the link 55 and stem 49, holds the valve holder 43 and the valve 47 thereon up, for outlet of liquid through the nozzle 40 into the container A held on the front scale pan or table 12 while weights B of the desired amount 100 occupy the rear pan or table 12 (Fig. 1). With the push-rod 66 adjusted to the proper height in its clamp-head 67, the instant that the container A has received the weight of liquid to balance the weights B, the rear 105 pan or table 12 is raised, engaging the part 68 of the push-rod 66 with the lever 57, raising the rear lever arm and lowering the front lever arm, away from the pawl part of the element 54. The valve elements inside 110 the spout, thus released, fall very quickly, by their own weight and that of the "head" 115 of liquid theretofore rushing past the valve. The supply of liquid to the container thus is shut off at practically the instant it has reached the desired weight in the container, without lag of the valve parts; and, owing to the constant "head" maintained by the toggle and float in the reservoir, the closing influence of this "head" is 120 practically constant, so that the minute time factor of closing always can be accurately compensated for in the construction of the machine. The very sudden closing of the outlet valve is cushioned by the dash-pot, so 125 that noise and wear of the parts is minimized.

Where containers of greater or less height are to be filled, the entire scale can be adjusted down or up on the standard 2 and 130

then held rigidly in its new position. The push-rod 66 can be correspondingly adjusted in its clamp-head, to engage properly with the lever 57. Also, where the containers vary much in size, it is desirable to change nozzles 40; the very large nozzle not fitting a small container neck with its discharged stream, and the very small nozzle, of course, being too slow in its discharge 10 for economically filling the large containers, permitting large discharge stream into their larger necks. Also, as the small valve for a large nozzle would limit its capacity, it is desirable to have the valves changeable 15 with the nozzles. This is very readily done, with my invention, by unscrewing the nozzle 40, allowing the valve holder 43 with the valve 47 thereon to drop partly from the lower end of the spout part 38, as is permitted 20 by the controlling connections previously described, and slipping the valve off the holder sidewise; the substitute larger or smaller valve being slipped onto the holder and returned up into the spout, and the 25 substitute corresponding nozzle being screwed in place on the spout end.

Certain constructional details have been described specifically herein, and these are preferable in connection with my invention, 30 but I do not wish to be understood as being limited to such precise showing and description, but having thus fully described my invention,

What I claim as new and desire to secure by Letters Patent is:

1. In a filling machine, a reservoir having an inlet, a valve controlling said inlet to said reservoir, a float in said reservoir, a toggle connected to said valve and to said 40 float, a spout leading from said reservoir, a weighing scale extending under said spout to hold a container thereunder, and means whereby said scale controls outlet from said spout.

45 2. In a filling machine, a reservoir, a spout leading from said reservoir, a weighing scale extending under said spout to hold a container thereunder, a valve controlling outlet from said spout, a member connected 50 to said valve, a lever retentively engaging said member to hold said valve open, means connected to said scale to release said lever from said valve-connected member, and a dash-pot having a plunger engaged by said member on release, to cushion closing of 55 said valve.

60 3. In a filling machine, a standard, a reservoir on said standard, a float-actuated valve controlling inlet to said reservoir, a spout leading from said reservoir downwardly, a nozzle detachably mounted on said spout, having an interior valve seat, a valve holder guided inside said spout, a valve detachably mounted on said holder to engage 65 said seat, a weighing scale mounted on said

standard and extending under said spout to hold a container thereunder, and means whereby said scale controls movement of said valve holder.

4. In a filling machine, a standard, a 70 reservoir mounted symmetrically on top of said standard, a spout leading from said reservoir radially to said standard and having an upright part with a bottom outlet having a valve seat therearound, a casing 75 leading up from said upright part alongside said reservoir and having a guide opening in its top, a valve for said seat, sliding in said upright part, a stem on said valve extending up through said casing and guide 80 opening, a shaft journaled transversely on said spout, radial elements fixed on said shaft at opposite sides of said spout, a rod connecting one element to said stem above said casing, a weighing scale having a beam 85 with separate members straddling said standard and extending under said spout to hold a container thereunder, a lever retentively engaging the other radial element to hold said valve open, and means connected to said scale to release said lever from 90 said other radial element.

5. In a filling machine, a standard, a 95 reservoir mounted symmetrically on top of said standard, a spout leading from said reservoir radially to said standard, a valve in said spout, controlling outlet therefrom, and having a connection extending outside said spout, a rocking member mounted across said spout and operatively related 100 to said valve connection at one side of said spout, a lever retentively engaging said member at the other side of said spout, to hold said valve open, a scale having a beam with separate members straddling said standard and extending under said spout to hold a container thereunder, and means connected to said scale to release said lever from 105 said rocking member.

6. In a filling machine, a standard, a 110 reservoir on said standard, a spout leading from said reservoir, a weighing scale having a beam with separate members straddling said standard and extending under said spout to hold a container thereunder, and having an opposite part to be weighted, beyond said standard from said spout, rising when the container is filled, a valve controlling outlet from said spout, a member connected to said valve, a lever retentively engaging said member to hold said valve open 115 and having a part beyond its fulcrum, extending beyond said standard, and means connected to said opposite part of said scale to engage this extended part of said lever and release said lever from said member as the scale part rises.

7. In a filling machine, a standard, a 120 reservoir mounted symmetrically on top of said standard, a spout leading from said 125

- reservoir radially to said standard, a yoke embracing said standard, a weighing scale having a beam fulcrumed on said yoke with separate members straddling said standard 5 and extending under said spout to hold a container thereunder, and means whereby said scale controls outlet from said spout.
8. In a filling machine, a standard, a reservoir mounted symmetrically on top of 10 said standard, a spout leading from said reservoir radially to said standard, a yoke embracing said standard and adjustable up and down thereon a weighing scale having a beam fulcrumed on said yoke and extending under said spout to hold a container thereunder, a valve controlling outlet from 15 said spout, a member connected to said valve, a lever retentively engaging said member to hold said valve open, and means connected to said scale for adjustment up 20 and down thereon, to release said lever from said member when said yoke, carrying said scale, is adjusted to various heights.
9. In a filling machine, a reservoir, a filling spout leading from said reservoir, and 25 a weighing scale in receptive relation to said spout, said reservoir, said spout and said scale all being symmetrical to a single vertical plane, controlling means at one side of said spout, under said reservoir, in operative relation to said scale, and extending across said spout, a valve controlling outlet from said spout, and a connection from said controlling means to said valve, at the opposite side of said spout, whereby said scale 30 controls said valve.

KARL KIEFER.
